UNITED STATES PATENT OFFICE.

MOSES G. CRANE, OF NEWTON, MASSACHUSETTS.

ELECTRIC BELL.

SPECIFICATION forming part of Letters Patent No. 388,836, dated September 4, 1888.

Application filed April 9, 1888. Serial No. 270,045. (No model.)

To all whom it may concern:

Be it known that I, MOSES G. CRANE, of Newton, county of Middlesex, State of Massachusetts, have invented an Improvement in 5 Electric Bells, of which the following description, in connection with the accompanying drawings, is a specification, like letters on the drawings representing like parts.

The object of my invention is to produce an 10 electric bell capable of being controlled by a current of moderate strength, such as commonly employed in a normally-closed circuit or main line for a fire-alarm telegraph or similar apparatus, and which is operated to 15 strike the blow upon the gong by a stronger current applied only while the bell-hammer is making its forward movement to strike the blow.

It is necessary in order to strike a sufficient 20 blow on a large bell that the hammer should have a long and forcible stroke, which, if the hammer is actuated directly by the magnet, involves a considerable separation of the armature from the magnet-poles. It is well known 25 that the attractive force diminishes rapidly as the distance of the armature from the poles increases, and for this reason it has been impracticable to operate large-sized bells by the direct action of the currents commonly employed in normally-closed telegraphic circuits, and such large-sized bells have usually been operated by a mechanical motor and controlled 30 only by the electric current.

In the present invention the bell-hammer is 35 actuated by the strong current of a powerful battery which is normally in open circuit; but its operation is controlled by the weaker current in the normally-closed circuit, which is sufficient to hold the armature when near the 40 poles of the magnet.

The invention is embodied in an apparatus 45 comprising an electro-magnet and its armature, a bell-hammer connected with and operated by the said armature, and an electric switch operated by the said bell-hammer at the end 50 of its movements in each direction, combined with a main circuit and circuit-controller which govern the operation of the said bell-hammer, and a local circuit and battery there- 55 in governed by the switch operated by the

bell-hammer, said local circuit being closed at the end of the back-stroke and opened at the end of the forward stroke of the bell-hammer, so that its current actuates the said bell-hammer in its forward movement, by which the 55 blow is struck, (or conversely.) A locking device is also provided for arresting the bell-hammer in its forward position independently of the attraction of its magnet, so that it will not fall back or be retracted on the opening of 60 the local circuit at the end of the forward stroke. The said lock or catch retains the bell-hammer and armature in the forward position near the poles of the magnet, but admitting of a slight additional forward movement 65 when the magnet is energized by the action of the main or controlling circuit, such slight additional forward movement releasing the lock or catch, so that the bell-hammer can make its return movement when the magnet is demagnetized by the subsequent action of the main 70 circuit, this construction insuring that the bell-hammer will respond with a single blow to each complete change or closure and subsequent break of the main circuit.

Figure 1 is a front elevation of an electric bell embodying this invention, the circuits being shown in diagram; Fig. 2, an enlarged perspective view of the lock for the bell-hammers, and Fig. 3 a detail showing the construction of the magnet-poles and armature in elevation on a plane at right angles to that of Fig. 1.

The instrument comprises a controlling and actuating electro-magnet, *a*, and armature *b*, 85 pivoted at *b'* and provided with an arm, *b''*, the extremity of which constitutes the bell-hammer *b³*, the said armature and bell-hammer being preferably made in a single casting of malleable iron.

The poles *a'* of the magnet *a* have large extensions, which may be made integral with the core-piece in the casting or may be fastened upon the said core piece, said pole-pieces *a'* having lugs *a²*, between which are pivoted lugs 95 *c*, composed of brass or other non-magnetic material attached to the armature, which is thus pivoted directly upon the poles, although not affording a direct magnetic-contact connection between the poles when the armature 100

is retracted. This construction of the magnet and its armature is not herein claimed, as it forms the subject of another application for Letters Patent.

5 In the forward movement of the armature produced by the attraction of the magnet *a* it is arrested by a stop, *d*, so that the hammer *b* will not remain in contact with the gong (a portion of which is shown at *e*) after the blow is struck.

10 The hammer and armature may be retracted by gravity when the instrument is set in proper position; but the armature is shown as provided with a retracting-spring, *f*, and it also has a spring-finger, *g*, which arrests the hammer at the end of the stroke by coming in contact with a stationary stop, *g'*, as shown in dotted lines, Fig. 1, thus stopping the hammer without shock and tending to start it 15 with an elastic impulse on its forward stroke.

15 The armature and the hammer just at the end of the stroke in each direction engage and operate a switch, *h*, pivoted at *h'* and provided with cam-surfaces *h*² *h*³, which are engaged by an actuating projection, *h*⁴, on the hammer-arm moving the end of the switch onto and off from a contact-plate, *i*, and thus closing and opening a circuit terminating in said switch and contact-plate at the end of the 20 backward and forward strokes of the hammer, respectively, and leaving said switch closed during substantially the whole forward stroke, and open during substantially the whole backward stroke, of the hammer.

25 35 The operation of the bell is controlled by a main circuit, 2 3 4 5, including a battery, *B*, and a circuit-changer—such, for example, as the break-wheel *C*—the said main circuit, as shown in this instance, including the magnet *a*, and its current being sufficient to retain the armature *b* attracted when the said armature is close to the poles of the magnet, but not necessarily being sufficient to move up the armature from its retracted position with sufficient force to give the desired stroke on the bell. The bell-hammer would thus respond to a break in the main circuit by falling back, and when it is once released or permitted to fall back by the main circuit its forward stroke 40 is produced independently of the action of the main circuit by means of the local circuit 6 7 8, connected with the terminals 3 4 of the magnet *a* and including a battery, *B'*, the said local circuit terminating in the switch *h* and its contact-plate *i*, so that the moment the said switch is closed by the action of the pin *h*⁴ on the cam *h*² at the end of the backward stroke, permitted by the breaking of the main circuit, as just described, the current of the battery *B'* 45 50 55 60 65 passes through the magnet *a* and causes the armature and hammer to make the forward stroke, by which the bell is struck.

65 The battery *B'* is normally in open circuit and may be sufficiently strong to cause the hammer to strike a powerful blow, and it will not be rapidly exhausted, as it works only during the forward stroke of the bell-hammer,

at the end of which the projection *h*⁴ engages the cam *h*³ and opens the local circuit.

If the break in the main circuit is only momentary, so that it closes again before the hammer finishes its forward stroke, it will retain the armature attracted, so that only one stroke will be given for such momentary break in the main circuit; but it will be seen that if the break in the main circuit should continue beyond the time occupied by the hammer in making its complete backward and forward movement—as, for example, by an accidental rupture of the main line—the said hammer 70 might continue to operate under control only of the local circuit and switch, like an automatically-vibrating bell, which may not be desirable. In order to guard against this and to insure that the bell-hammer will make only 75 one stroke for each break in the main circuit, it is provided with a lock, *m*, made movable in such manner as to permit the forward and backward strokes of the bell-hammer at the proper times, but to arrest the bell-hammer 80 after it has completed its forward stroke in case the magnet *a* is not energized by the action of the main circuit at this time. The lock *m* is shown in this instance as movable on a pivot, *m'*, and normally, when free to move, is 85 held against a stop, *m*², by the action of a light spring, *m*³, or weight such as indicated in dotted lines at *m*⁴.

90 The hammer-arm *b*² is provided with a projection, *n*, that co-operates with the lock *m*, and the said lock is provided with a groove, *m*⁵, which, when the said lock is held against its stop *m*², is concentric with the pivot *b'* of the armature, so that the projection *n* will pass freely through said groove in the back-stroke 95 of the hammer. The lower end of the said groove is closed by a light spring, *n*⁶, which yields to permit the projection *n* to pass as the hammer makes its back-stroke, but closes over the end of the groove *n*⁵ immediately after the projection *n* has passed through, so that when the hammer makes its forward stroke the projection *n* will engage the said spring *n*⁶, and thus, instead of passing through the groove *n*⁵, as it did on its downstroke, it will pass 100 along the front of the lock *m*, turning the same on its pivot to the position shown in dotted lines, Fig. 1.

105 Immediately after the projection *n* has passed the front of the lock *m* and turned it aside on its pivot, as just described, the said lock will tend to return to its normal position against the stop *m*² by the action of the spring *m*³ or weight *m*⁴, but it will occupy little time in coming to this position, and if the magnet *a* be not 110 energized when the hammer completes its forward stroke the latter will move back almost instantly by its rebound, and will thus strike on the upper end, *m*¹, of the lock before the latter is moved far enough to bring the 115 groove *n*⁵ in line with the said pin *n*, thus preventing the armature and hammer from moving back. The downward or backward pressure of the bell-hammer will prevent further 120 125 130 135

movement of the lock, which will thus retain the armature close to the magnet-poles as long as the magnet remains demagnetized. The end of the lock may be provided with a slight projection, m^s , to insure greater certainty of engagement with the pin n in case the hammer begins to make a return movement immediately after its forward stroke. The hammer will remain thus locked in position, with the armature close to the poles of the magnet, until the main circuit is closed, when the armature will be again attracted, and the relieving of the pressure of the pin n upon the upper end of the lock m and slight forward movement of the armature will permit the latter to be turned by its weight or spring to the normal position with the groove n^s in the path of the projection n , so that it can make another stroke, as before described, upon the breaking of the main circuit. By this construction it will be seen that the bell-hammer is completely under control of the main circuit, making a single stroke only when the proper change in the main circuit occurs, and it is actuated wholly, or substantially so, by the current in the local circuit, although if the main circuit should be closed before the hammer had finished its forward stroke it might contribute to some extent to the force of the magnet that produced such stroke.

I claim—

1. The combination of an electro-magnet and armature therefor normally held in advance of its retracted position with a switch operated by said armature at the ends of its movements toward and from the poles of the magnet, a local circuit through the said magnet controlled by the said switch, and a main circuit governing the operation of said magnet, whereby the armature is moved up to the poles of the magnet by the current of the local circuit after it is permitted to fall back by a momentary change in the main circuit, substantially as described.

45 2. The combination of an electro-magnet and

its armature with a switch operated by the said armature at the end of its movement toward and from the poles of the magnet, an electric circuit through said magnet controlled by said switch, and a lock that co-operates with said armature, substantially as described.

3. The combination of an electro-magnet and its armature with a lock normally held, when said armature is attracted, in the position to permit the retractive movement of said armature and engaged and moved from said normal position by the armature in making its forward stroke, the said lock having a portion that in the movement of the lock from the position in which it is placed by the armature making its forward stroke to its normal position affords an obstruction to the return movement of the armature, substantially as described.

4. The combination of an electro-magnet and armature therefor normally held in advance of its retracted position with main and local circuits through the coils of said magnet, each containing a source of electricity, and a circuit-closer in said local circuit operated by the armature of said magnet, the members of which are separated when said armature is in its normal position and are engaged and placed in contact when said armature is in its retracted position, as and for the purpose described.

5. The combination, with the armature-lever provided with an engaging projection, of the lock for said armature-lever provided with a groove normally in the path of said projection when the armature makes its retractive movement and a spring closing the said groove and engaged by the said projection when the armature makes its forward movement, substantially as described.

In testimony whereof I have signed my name to this specification in the presence of two subscribing witnesses.
